(57) **CLAIM**

The ornamental design for an interdental brush handle, as shown and described.

DESCRIPTION

FIG. 1 is a top perspective view of an interdental brush handle showing the new design;

FIG. 2 is a bottom perspective view thereof;

FIG. 3 is a top plan view thereof;

FIG. 4 is a bottom plan view thereof;

FIG. 5 is an elevational view of one end of the interdental brush handle;

FIG. 6 is an elevation view of the other end of the interdental brush handle; and,

FIG. 7 is a side elevational view thereof.

The broken lines of the drawings represent surface shading showing one or more of surface contours and tangencies of the new design.
